UNITED STATES PATENT OFFICE.

SAM YODER, OF BLACKWELL, OKLAHOMA.

CORNER PIECE FOR BUILDINGS.

Application filed June 8, 1925. Serial No. 35,625.

The present invention relates to improvements in corner pieces for buildings, and has for its principal object to provide structural elements which are exceedingly simple, strong, durable, easy to incorporate in the building, attractive in appearance, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:—

Figure 1 is an elevation of one embodiment of the invention, and

Figure 2 is an elevation of another embodiment of the invention.

Referring to the drawing in detail, it will be seen that the two embodiments consist of two end receiving members for the walls at a corner of a building, these members being indicated by the letters A. Each member A consists of a relatively short leg 5 and a relatively long leg 6. These legs 5 and 6 are disposed at right angles to each other. In Figure 1, the shorter legs 5 are provided with outwardly extending right angularly disposed extensions 9 which are folded upon themselves and connected by the straight segment 10, thereby forming a triangular corner piece with lips. In Figure 2, the legs 5 have outwardly extending rectangularly disposed extensions 13, the ends of which are connected by the arcuate segment 14.

With this device it is possible to make a very strong and durable corner with very little effort of a laborious nature so that the installation may be cheaply accomplished. The pieces should be made from single sheets of galvanized iron or the like.

It is thought that the construction, utility, and advantages of the invention will be clearly understood without a more detailed description thereof. It is apparent that numerous changes in the details of construction, and in the combination and arrangement of parts may be resorted to without departing from the spirit or scope of the invention as hereinafter claimed or sacrificing any of its advantages.

Having thus described the invention, what I claim as new and desire to secure by Letters Patent is:—

A device of the class described including a pair of wall end receiving members, each member comprising a pair of right angularly disposed legs, one leg being larger than the other of each member, the long leg of one member being substantially aligned with the short leg of the other member, the short legs of the members being right angularly disposed to each other and the long legs of the members being right angularly disposed to each other, and a member including a body portion having its ends bent over upon itself and integrally merging into the terminals of the short legs for connecting said first mentioned members together.

In testimony whereof I affix my signature.

SAM YODER.
